UNITED STATES PATENT OFFICE

EDWARD MILLER, OF HUNTINGTON PARK, CALIFORNIA, ASSIGNOR TO EVANS AUTO LOADING COMPANY, INC., OF DETROIT, MICHIGAN, A CORPORATION OF DELAWARE

RIVING MACHINE

Application filed June 24, 1929. Serial No. 373,159.

This invention relates to riving machines, in machines as heretofore constructed where and has for its principal object the provision of a new and novel construction whereby strips of veneer of relatively great length and of uniform thickness may be obtained.

Another object is to provide a riving machine including a knife of relatively great length, means being provided for preventing distortion or springing of the knife during the cutting operation.

Another object is to provide a riving machine including a table of relatively great length, means being provided for preventing distortion or springing of the table during the cutting operation.

Another object is to provide a riving machine by which lattice or other strip-like pieces of veneer may be removed from an elongated piece of wood stock.

20 A further object is to provide a riving machine in which the veneering removed from the block of stock will be automatically ejected from the machine.

The above being among the objects of the present invention, the same consists in certain novel features of construction and combinations of parts to be hereinafter described with reference to the accompanying drawings; and then claimed, having the above and other objects in view.

In the accompanying drawing which shows a suitable embodiment of the present invention, and in which like numerals refer to like parts throughout the several different views;

25 Fig. 1 illustrates a more or less diagrammatic fragmentary plan view of a riving machine.

Fig. 2 is an enlarged sectional view taken on the line 2—2 of Fig. 1, certain parts thereof being broken away to better illustrate the construction.

30 Fig. 3 is a more or less diagrammatic view illustrating the manner in which the strips of veneer are automatically ejected from the machine.

In riving machines as heretofore constructed, it has been impossible to cut veneer-like strips of any appreciable length and of uniform thickness throughout. The reason for this has been impossible is due to the fact that

a knife and a table of relatively great length were employed, the pressure of the stock being cut, between the cutting edge of the knife and the cooperating edge of the table, causes

the cutting edge and the table to spring away from each other along the central portions thereof, with the result that the central portion of the veneer strip is of greater thickness than the thickness of the ends, which end

thickness is that desired throughout the entire strip. The greater the pressure of the stock between the cutting edge of the knife and the table, the greater has been the variation of thickness in the strip being cut, and

55 inasmuch as it is desirable for other reasons to obtain a relatively great amount of pressure between the cutting edge of the knife and the table during the cutting operation,

60 no means have heretofore been provided in a commercially practicable machine which would permit the employment of the requisite pressure without causing an undue flexure

65 of the cutting edge and table, with resulting commercially unsatisfactory products. By

70 the use of the present invention, a construction is provided by which veneer strips of relatively great length may be cut, and in which the thickness of the strips being cut

75 will be maintained at a constant dimension throughout the entire area of the strip.

80 Referring to the accompanying drawing, I show a riving machine comprising a pair of rigid stationary angular side bars 10 between

85 which a frame comprising rigid side members 11 and end members 12 is slidably received and adapted to reciprocate. Extending

90 between the side members 11 of the frame from one end to the other in relatively close but spaced relationship, is a plurality of cross members 13. These cross members 13

95 are preferably formed as illustrated in Fig. 2, to resist a maximum amount of bending in a vertical plane. A knife supporting member 14 is formed independently of the

100 reciprocable frame, and may be secured thereto in any suitable manner such as at its end by bolts 15. The supporting member extends from one end cross member 12 to the

105 opposite end cross member 12 at a relatively

slight angle to the path of movement of the reciprocable frame. This supporting member 14 extends over the various cross members 13 in relatively close but spaced relationship to the upper surfaces thereof. In line with each of the cross members 13 the member 14 is provided in its lower face with a T-shaped slot 16 extending in parallel relationship to the upper surface of the corresponding cross member 13. A bolt 17 having an enlarged head 18 which is slidably received in the corresponding slot 16 extends downwardly from each of the slots 16 through the corresponding cross member 13 and is provided below the cross member 13 with a nut 19. A knife 20 having a cutting edge 21 is secured to the upper face of the member 14 in parallel relation with respect thereto and may be secured to the member 14 by any suitable means, as by screws 22 as indicated in Fig. 2.

A table 23 having a thickened edge portion 24 extends from one end of the frame to the other end thereof with the thickened edge thereof lying below and in spaced and parallel relationship with respect to the cutting edge 21 of the knife 20. The ends of the table 23 may be secured to the end members 12 by screws such as 25, or other suitable means. The under surface of the table 23 and the thickened portion 24 extend above and in spaced relation to the upper surface of the various cross members 13.

Through each of the cross members 13 is vertically threaded a pair of bolts 25 and 26, the bolt 25 bearing against the lower face of the portion 24, and the bolt 26 bearing against the under face of the opposite edge of the table. If desired, a plurality of bolts such as 27 may slidably extend through each of the cross members 13 and thread into bosses such as 28 formed on the lower side of the table, so as to maintain the table in contact with the upper ends of the bolts 25 and 26. The table 23 is preferably further provided with a so-called "pressure bar" 29 projecting above its upper surface directly below the cutting edge 21. By adjusting the bolts 25 and 26, the angularity of the surface of the table 23 may be varied with respect to the plane of movement of the cutting edge 18, as will be apparent. This feature, however, is incidental to the main purpose of the bolts 25 and 26, as will hereinafter be apparent.

The knife preferably recedes downwardly away from the plane of movement of the cutting edge 21 from the cutting edge 21, for the reasons described in my application for Letters Patent of the United States for improvements in Riving machines, filed August 27, 1928, Serial Number 302,209. The knife 20 and table 23 are extended at an angle to the path of movement of the knife for reasons described in my application Serial

No. 373,158 for Letters Patent in the United States for improvements in Riving machines filed on even date herewith. The table 23 preferably recedes downwardly away from the plane of movement of the cutting edge 21 away from the pressure bar 29, for the reasons described in the above application filed on even date herewith.

The side members 10 carry a stationary frame comprising cross members 30 connected together by the spaced parallel members 31 which serve to support the hopper comprising the vertically extending plate-like members 32 between which the block of stock 33 is vertically slidably received. The hopper is preferably so positioned that the block of stock 33 extends in almost but slightly out of parallel relationship with respect to the cutting edge 21, for a reason that will be hereinafter explained, the relation being such that during operation of the machine the right hand end of the block of stock 33 will be engaged by the cutting edge 21 slightly in advance of engagement of any other part of the block of stock 33. As explained in my application filed on even date herewith, above referred to, this relative position of the block of stock 33 and cutting edge 21, results in a true slicing action of the knife on the block of stock.

In operation it is, of course, evident that as the reciprocable frame is reciprocating, carrying the knife 20 and table 23 with it, each time the knife 20 moves out from under the block of stock 33 the block of stock is pressed downwardly into contact with the table 23, so that upon the succeeding stroke of the reciprocating frame the cutting edge will pass through the block of stock 33 and remove therefrom that portion thereof positioned below the plane of movement of the cutting edge 21. As previously explained, where an extremely long knife such as 21 and table 23 is employed, the constructions as heretofore provided have been such that the pressure of the stock between the cutting edge 21 and the table 23, or more correctly, in the present construction, between the cutting edge 21 and the pressure bar 29, has been sufficient to cause a material amount of flexing of the knife and the table away from each other and to result in a strip of veneer being cut from the block of stock which has a materially greater thickness at its center than at its ends, and as previously pointed out, this variation of thickness has been so great as to prevent a commercially acceptable product of a relatively great length from being produced by a riving machine. Such springing or flexing of the knife and the table is prevented in the present construction by the means described.

The tendency of the knife to distort is in an upward direction and the tendency of the table is to distort in a downwardly direction.

Consequently, with the construction described, the tendency of the knife to distort upwardly is counter-acted by the bolts 17 which tie the member 14 and therefore the knife 20, to a definite and predetermined relationship with respect to the cross members 13 which are of sufficient rigidity to withstand such distorting tendency of the knife. The tendency of the table to distort downwardly is offset by the screws 25 and 26 which maintain the table in a predetermined and definite relationship with respect to the cross members 13. By suitably adjusting the screws 17, 25 and 26, it will thus be apparent that the relation between the cutting edge 21 and pressure bar 29 which is carried by the table 23, may be initially set at a predetermined dimension and thereafter its dimension be maintained regardless of a relatively great pressure between the cutting edge 21 and pressure bar 29 tending to separate the cutting edge 21 from the pressure bar 29.

I have found that by supporting the table and the knife-supporting member in this manner I am enabled to obtain strips of veneer from a block of stock of any length desired; for instance, twelve feet, or even greater length. Thus this machine is particularly adaptable for the production of the slats employed in the formation of Venetian blinds, and by being able to produce such slats on a riving machine instead of sawing them as has heretofore been necessary to obtain a product of the desired uniformity, I am enabled to produce such Venetian blinds at a considerably lower cost than has heretofore been possible.

Another feature of the present invention is the automatic ejection of the veneer strips cut from the block of stock, and in a direction longitudinally of the machine. This is partly the result of positioning the block of stock 33 at a slight angle to the cutting edge 21 so that the outer end of the block of stock (the left hand end in Fig. 1) is the last end of the block to be operated upon by the knife, and also partly due to the fact that I position the block 33 at an extremely acute angle to the path of travel of the knife. It will be apparent that when the strip of stock is severed from the block 33 it will fall between the member 14 and the part 24 of the table, and extending over the various cross members 13 at this point, I prefer to place a strip of sheet metal such as 35 to form a table-like support for the strips such as 36 which are removed from the block of stock 33. With this construction, and with the block of stock 33 positioned as explained, it will be apparent that the upper left-hand corner of the block 33 will be the last part of the block 33 to be acted upon by the knife edge 21 during the removal of a strip therefrom. By the time the cutting edge has

reached this corner of the block of stock 33, the righthand end of the strip which is being severed from the block 33 will have passed into the space between the member 14 and the portion 24 of the table, and will have dropped down onto the table member 35. I have found that the last corner of the strip of stock being severed will not fall down of its own accord out of the table 35, but will remain caught between the cutting edge 21 and the pressure bar 29 so that as the frame carrying the table and the knife returns on its non-working stroke, it will carry this strip 36 back with it to the end of such stroke, and as it commences on its next working stroke, the righthand end of the next strip 36 to be cut (as viewed in Fig. 1) will strike the end of the previously cut strip 36 and force it out of engagement between the cutting edge 21 and the pressure bar 29 so that it will fall down onto the table 35, and the end of the strip now being cut will remain in substantially abutting and aligned position with respect to the left hand end of the previously cut strip 36, so that as the strip 36 now being cut begins to move to the right during the next non-working stroke of the reciprocating frame, its right hand end engaging the left hand end of the previously cut strip will force such previously cut strip to the right (as viewed in Fig. 1) along the table 36 and eject it from the machine. This action continues between each of the strips being cut and the previously cut strip, so that all the strips are automatically ejected endways of the machine. This relation of the strips is shown in a more or less diagrammatic manner in Fig. 3.

Formal changes may be made in the specific embodiment of the invention described without departing from the spirit or substance of the broad invention, the scope of which is commensurate with the appended claims.

What I claim is:

1. In a riving machine, in combination, an elongated reciprocable frame having rigid side members, an elongated knife carried by said frame, a plurality of rigid cross members extending between said side members, and means cooperating between said knife and said cross members for maintaining said knife from flexing in one direction.

2. In a riving machine, in combination, a reciprocable frame having a plurality of cross members, a knife carried by said frame, and means cooperating between said cross members and said knife adjustably limiting movement of said knife away from said cross members.

3. In a riving machine, in combination, a reciprocable frame having side rails, a plurality of cross members extending between said side rails, a knife supporting member extend-

ing over said cross members in spaced relation thereto, and means extending between said supporting member and said cross members limiting movement of said supporting member away from said cross members.

4. In a riving machine, in combination, a reciprocable frame having side rails, a plurality of cross members extending between said side rails, a knife supporting member extending over said cross members in spaced relation thereto, and adjustable means extending between said supporting member and said cross members limiting movement of said supporting member away from said cross members.

15. In a riving machine, in combination, a reciprocable frame having side rails, a plurality of cross members extending between said side rails, a knife supporting member extending over said cross members in spaced relation thereto, and screw means extending between said supporting member and said cross members limiting movement of said supporting member away from said cross members.

20. In a riving machine, in combination, a reciprocable frame having side rails, a plurality of cross members extending between said side rails, a knife supporting member extending over said cross members in spaced relation thereto, said knife supporting member being provided with T-shaped slots in its under surface over each of said cross members, and bolts having heads received in said slots extending through said cross members and provided with means on the lower ends thereof for limiting the space between said supporting member and said cross members.

25. In a riving machine, in combination, a reciprocatory frame, a knife carried by said frame, a table carried by said frame in a predetermined relationship with respect to said knife, cross members on said frame extending under said table in spaced relationship with respect thereto, and means cooperating between said cross members and said table for maintaining said spaced relationship at a predetermined value.

30. In a riving machine, in combination, a reciprocatory frame, a knife carried by said frame, a table carried by said frame in a predetermined relationship with respect to said knife, cross members on said frame extending under said table in spaced relationship with respect thereto, and screw means cooperating between said cross members and said table for maintaining said spaced relationship at a predetermined value.

35. In a riving machine, in combination, a reciprocatory frame, a knife carried by said frame, a table carried by said frame in a predetermined relationship with respect to said knife, cross members on said frame extending under said table in spaced relationship with respect thereto, and members threaded through said cross members and

bearing against said table for preventing downward flexing of said table beyond a predetermined position.

40. In a riving machine, in combination, a reciprocatory frame, a knife carried by said frame, a table carried by said frame in a predetermined relationship with respect to said knife, cross members on said frame extending under said table in spaced relationship with respect thereto, and screw means cooperating between said cross members and opposite said side edge portions of said table for limiting the spaced relationship between said table and said cross members and for controlling the angular relationship of said table relative to the plane of movement of said knife.

45. In a riving machine, in combination, a reciprocatory frame, a knife carried by said frame, a table carried by said frame in a predetermined relationship with respect to said knife, cross members on said frame extending under said table in spaced relationship with respect thereto, members threaded through said cross members and bearing against said table for preventing downward flexing of said table beyond a predetermined position, and means for maintaining said table in contact with said members.

50. In a riving machine, in combination, a reciprocatory frame, a knife and a table carried by said frame, said knife and said table extending into spaced but adjacent relationship, and means for maintaining said spaced relationship at a predetermined relationship during the separating influence of a cutting operation comprising cross members carried by said frame, and screw members cooperating between said cross members and said knife and said table.

55. In a riving machine, in combination, a reciprocatory frame, a knife and a table carried by said frame, said knife and said table extending into spaced but adjacent relationship, and means for maintaining said spaced relationship at a predetermined relationship during the separating influence of a cutting operation comprising cross members carried by said frame, and screw members cooperating between said cross members and said knife and said table and acting in opposite directions relative thereto.

60. In a riving machine, in combination, a reciprocable frame, a knife carried by said frame with its cutting edge disposed at an acute angle to the path of movement of said frame, an elongated block of stock, means for supporting said stock in position to be operated upon by said knife and disposed with a side edge thereof at a slight angle to the cutting edge of said knife, and a guide-way positioned below and in relatively adjacent relation to said knife for receiving the

strips severed from said block of stock by said knife, whereby each strip cut from said block of stock will be deposited upon said guideway and be engaged by the strip next removed from said block of stock to eject the first mentioned strip from said machine.

EDWARD MILLER.
